UNITED STATES PATENT OFFICE.

LEVITT E. CUSTER, OF DAYTON, OHIO.

DESIGN FOR AN ELECTRICAL MUFFLE-CASING.

SPECIFICATION forming part of Design No. 25,843, dated July 28, 1896.

Application filed June 1, 1896. Serial No. 593,930. Term of patent 3½ years.

To all whom it may concern:

Be it known that I, LEVITT E. CUSTER, a citizen of the United States, residing at Dayton, in the county of Montgomery and State 5 of Ohio, have invented and produced a new and original Design for a Casing for Electrical Dental Muffles, of which the following is a specification, reference being had to the accompanying drawings, forming part of this 10 specification, in which—

Figure 1 is a front perspective view of the muffle. Fig. 2 is a rear perspective view thereof.

The design for casing comprises a rectangular base and a body which resembles a sec- 15

tion of a cylinder stood on end and flattened on its front face with a conical opening in its front face and a conical opening in its rear upper edge.

The design consists in the configuration 20 and external appearance of the casing for electrical muffles as shown in the drawings.

What I claim as new is—

The design for a casing of an electrical muffle substantially as herein shown and de- 25 scribed.

L. E. CUSTER.

In presence of—

HARRY F. NOLAN,
S. RUDOLPH LIGHT.
